UNITED STATES PATENT OFFICE.

ELNATHAN COLE, OF LOS ANGELES, CALIFORNIA, ASSIGNOR TO COLE MANUFACTURING COMPANY, OF LOS ANGELES, CALIFORNIA, A CORPORATION OF CALIFORNIA.

GAS-HEATER.

1,126,617.

Specification of Letters Patent. Patented Jan. 26, 1915.

Application filed December 8, 1913. Serial No. 805,463.

To all whom it may concern:

Be it known that I, ELNATHAN COLE, a citizen of the United States, residing at Los Angeles, in the county of Los Angeles and State of California, have invented a new and useful Gas-Heater, of which the following is a specification.

My invention relates to the art of heating buildings, or portions thereof, by the heat 10 from burning gas.

The heating of buildings by the use of gas has been ordinarily accomplished in one of two manners, either small portable gas heaters are employed which are commonly attached to the gas supply by means of a flexible hose, or a gas heater is employed of the type that is placed in the basement of the house and pipes for the hot air being led from such a heater to the respective portions 20 of the house to be heated. In the first style of heater mentioned a serious objection may be raised thereto that the portable heater takes its supply of oxygen within the room and eventually burns up the greatest part of 25 the oxygen in the room at the same time liberating in the room the obnoxious products of combustion. Where the form of heater is employed which is placed in the basement, ordinarily the products of combustion are 30 carried away through a chimney, and the air which is used for heating the house is heated within a chamber of the heater and does not come in contact with the flame.

My invention consists primarily in providing 35 a gas heater of simple form and construction wherein the heated air from the combustion chamber of the heater is passed into the room and at the same time such air is mixed with a fresh supply of air either 40 from the exterior of the building or from the basement, and one of the main objects of my invention is to produce a gas heater of the class described which may be installed in a house at low expense.

Referring to the drawings which are for 45 illustrative purposes only: Figure 1 is a perspective of the portion of a building showing a heater, partly broken away, embodying the form of my invention. Fig. 2 is a vertical 50 sectional view of the heater shown in Fig. 1 together with a portion of the floor. Fig. 3 is a sectional plan view on the line x^3-x^3 Fig. 2.

The heater consists, in the form shown, of 55 a box 1 open at the top and formed of an

inner casing 2 and an outer casing 3 spaced apart therefrom. The space at the sides of the box between the inner casing 2 and the outer casing 3 is filled with asbestos, or other suitable non-conducting material indicated at 4. The upper edge of the outer casing 3 is turned outwardly to form a flange 5 which is secured in any suitable manner, as by screws 6, to the underside of a floor 7, the inner casing 2 and the non-conducting material 4 extending upwardly into a suitable opening formed in the floor 7. The bottom 8 of the inner casing 2 is provided with a series of perforations 9, and the bottom 10 of the outer casing 3 is similarly provided with a series of perforations 11 of somewhat larger diameter than the perforations 9 in the bottom of the inner casing 2.

The upper or open end of the box 1 is provided with a common form of floor register 12 suitably provided with closure vanes 13 and operated in the usual manner by a lever 13' at one end thereof. The floor register 12 is seated within a recess formed in the floor so that the upper face of the floor register is substantially flush with the upper face of the floor as is the usual custom.

The bottom 8 of the inner casing 2, and the bottom 10 of the outer casing 3 of the box 1 are each provided with a central opening circular in form through which extends the open end 14 of a pipe 15, the end 14 of the pipe being substantially vertical and the pipe 15 being substantially horizontal. The end 14 of the pipe extends upwardly in the box 1 substantially half of the distance from the bottom to the top of the box. It is clearly shown in Figs. 1 and 2 that the outer end of the pipe 15 extends through the wall of the house, and is covered at the outer end by means of a screen 16 for the purpose of preventing the entrance of animals or debris into the pipe 15.

The box 1 forms a combustion chamber 17 which is provided with heating means which consists of a gas pipe 18 which extends around the end 14 of the pipe 15 being spaced a short distance above the bottom 8 of the inner casing tube. The pipe 18 is provided with a series of gas jets 19 which are inclined inwardly and upwardly from the pipe 18 so that when the jets 19 are lighted the heat from the flames of the respective jets is directed upwardly and converges as a cone of heat above the open 110

end 14 of the pipe 15 for the purpose hereinafter described. These jets, as indicated in Fig. 2, are far enough below the open end 14 of the air pipe to place that open end practically above the flame zone of the burner, so that the column of fresh air which escapes from the upper end 14 is met and acted on, not by flames which would consume its oxygen, but by the heat from 10 said flames, which, converging into a cone-like body whose apex is some distance above the upper end of the fresh air pipe, acts effectively to heat the incoming fresh air after it emerges from the top of the air 15 pipe without sensibly affecting its quality. One end of the pipe 18 is closed by means of a suitable cap 20 and the other end 21 of the pipe 18 extends through the walls of the box 1 and is connected by means of a 20 suitable fitting 22 with a gas supply pipe 23, which supply pipe 23 is provided with a regulating valve 24, the stem of which extends upwardly through the floor 7 and is provided with suitable handle means 25 above the floor 7.

The gas heater above described may be placed within a dwelling in any suitable manner, but I prefer to place the same in the floor of the dwelling close to the partition wall 28 substantially as shown in Figs. 30 1 and 2, in which case the box 1 is under the floor, and the register being substantially flush with the floor, the heater forms no obstruction within the room. When it 35 is desired to place the heater in operation, the gas is turned on by means of operating the valve 24 by the handle means 25 and a lighted match inserted through the register 12, thereby lighting the jets 19. The 40 jets being arranged as heretofore described, direct the heat from the flames so as to converge above the open end of the pipe 15, thereby causing a draft of air through the pipe 15 and upwardly through the open end 45 14 thereof, thence through the register 12 into the room, the products of combustion from the jets 19 being thoroughly mixed with the air entering the box 1 through the pipe 15 thereby heating the fresh air and 50 causing a current of heated air to pass into the room to be warmed. Air also enters the combustion chamber 17 through the openings 9 and the openings 11 in the bottom of the respective casings 2 and 3 by means 55 of which fresh air is supplied directly around the jets 19 to aid in the process of combustion.

In using the heater above described it is to be noted that the room heated receives

substantially all of the heat generated by 60 the heater and the products of combustion being thoroughly mixed with a constant supply of fresh air from the exterior of the building, the bad effects ordinarily produced from a portable gas heater are overcome and the strong current of air ascending 65 upwardly into the room from the heater causes the air within the room to be agitated and moved so that the air within the room soon becomes heated throughout. 70 When the heater is not in use the vanes of the register 12 may be closed thereby preventing any dirt or objects from falling into the combustion chamber.

What I claim is:

1. In a gas heater, a suitable casing forming a combustion chamber; an air inlet pipe extending into said chamber with its open upper end located above the flame zone of the burner; a burner consisting of a series of gas jets surrounding said air pipe below the upper end thereof and directed upwardly and inwardly with reference to the same, so that the heat from their flames shall tend to converge and meet at a point 85 above said open upper end of the air pipe; means for supplying the jets with gas; and means for delivering air to the jets at the point of combustion.

2. A gas heater adapted to be supported in a floor comprising a box forming a combustion chamber open at the top; an air inlet pipe extending upwardly through the bottom of said chamber beyond the flame zone of the burner employed; a gas supply pipe in said chamber around said air inlet pipe below the upper end thereof; a burner consisting of a series of jets in said gas pipe directed upwardly and inwardly toward the open end of the air inlet pipe 100 so that the heat from their flames shall tend to converge and meet at a point above said open end of the air pipe; valve means for said gas pipe exterior to said chamber; and a register in the top of the combustion 105 chamber and arranged to deliver the contents thereof into the room above the floor, the bottom of said chamber having a series of air inlet perforations therein to supply air to the burning gas.

In testimony whereof, I have hereunto set my hand at Los Angeles, California, this 25th day of November, 1913.

ELNATHAN COLE.
